UNITED STATES PATENT OFFICE.

CARLOS FADER, OF LANDAU, GERMANY.

GAS-LIGHTING APPARATUS.

SPECIFICATION forming part of Letters Patent No. 697,080, dated April 8, 1902.

Application filed April 3, 1901. Serial No. 54,197. (No model.)

To all whom it may concern:

Be it known that I, CARLOS FADER, a subject of the German Emperor, and a resident of Mendoza, Argentina, actually at Landau, 5 Bavaria, Germany, have invented new and useful Improvements in Gas-Lighting Apparatus, (for which I have applied for a patent in France, dated January 10, 1901, No. 295,421; in Belgium, dated January 10, 1901, No. 122,153; in Germany, dated December 13, 1900, No. F. 13,603, and in Great Britain, dated January 14, 1901, No. 906,) of which the following is a specification.

As is well known, the lighting by hand of 15 street-lamps necessitates the employment of lamp-lighters, the number of which varies with the area to be lighted and involves a comparatively great expense in large cities. Although this expenditure is done away with 20 where cities are lighted by electricity, yet, owing to the brilliant light now obtainable from ordinary illuminating-gas by incandescence and owing to the great difference in the cost of the two illuminants—gas and electricity—the former being far the cheaper, the gas 25 incandescent system of lighting is being substituted for the costly electric-lighting system in many cities, and where new plants are installed the incandescent system is preferred 30 for reasons stated.

The object of this invention lies in a simple and reliable apparatus for automatically lighting and extinguishing gas-lamps of a city with a minimum loss or waste of gas, the lighting and extinguishing of the lamps being effected by simply varying the pressure of the 35 gas in the service-pipes, which may be effected at a central source of gas-supply or at any other suitable point or points within the area 40 to be illuminated.

That my invention may be fully understood, I will describe the same in detail, reference being had to the accompanying drawings, in which—

45 Figure 1 is a vertical sectional view of my improved automatic gas lighting and extinguishing device. Fig. 2 is a similar view thereof, showing a slight modification in the construction and operation of the valves and 50 in the means for igniting the flame at the burner; and Figs. 3 and 4 are fragmentary

sectional views, on a larger scale, of the apparatuses illustrated in Figs. 1 and 2, respectively.

Referring to Figs. 1 and 3, A indicates a 55 cylindrical casing provided in its lower head with an internally-screw-threaded neck which is screwed onto the gas-supply pipe B, that projects into said casing a proper distance. C indicates the cover or upper head for said 60 casing removably secured thereto in any suitable manner and has dependent therefrom a cylinder d, whose open end is close to the lower head of said casing. The cylinder d is of less diameter than the casing A and concentric therewith to divide the same into two 65 chambers, and into the outer chamber extends an overflow-pipe Q, whose outer end screws into an internally-screw-threaded bearing in the lower head of casing A, so that 70 the inner end of said pipe may be adjusted relatively to the outlet of the gas-supply pipe B, and consequently relatively to the displacement of the liquid in the apparatus, as hereinafter referred to, the head C of said 75 casing being provided with an aperture i for the introduction of such liquid, which aperture is always open, so that the pressure therein will always be equal to atmospheric pressure. 80

The head C of casing A is provided with two nipples a and a', having gas-passages therein, opening into the inner chamber of the apparatus—namely, into the cylinder d—the passage in nipple a being contracted at its inner end, forming a port t, and on the mouth of said nipple is seated a plate s', more clearly shown in Fig. 3, having a port s therein of less cross-sectional area than the passage in said nipple, said ports being controlled by a 90 valve, as hereinafter explained, the plate being held in position by a screw-cap constituting the base or support for a Bunsen burner F, provided with means for supporting an incandescent mantle. (Not shown.) The nipple a' also has a gas-passage e opening into cylinder d, the outer end of said passage being enlarged and screw-threaded internally for the reception of the igniter-burner pipe H, at the outlet of which is mounted, 95 preferably so as to revolve, a platinum-sponge carrier j, which constitutes the igniter for ig- 100

niting the gas issuing from the pipe H and therethrough the gas issuing from the main burner, in a well-known manner.

In the passage through nipple a' and held 5 in position by pipe H is arranged a plate x' , more clearly shown in Fig. 3, provided with a port x , controlled by a valve.

The valve which controls the ports s and t is a double cone-valve r , secured to a stem o , 10 which carries a float M , secured to a sleeve secured to said stem and guided in bracket p on cylinder d , the sleeve having at its upper end a flange or other projection serving to limit the drop of the float by contact with 15 said bracket.

The valve which controls the port x of the igniter is a cone-valve w , secured to a stem v , on which is likewise secured a float N , whose sleeve has also a flange or other projection y , serving to limit the drop of the float 20 N by contact with the guide-bracket p' on cylinder d for the valve-stem v .

It will be observed that the guide-brackets p and p' are so arranged relatively to the abutments or flanges u and y as to allow valve w but a slight movement from port x and to admit of sufficient movement of double cone-valve r to close port t as well as port s . It will also be observed that any suitable liquid 30 may be used with the apparatus, the nature of such liquid depending upon the conditions of use of the apparatus. When the latter is used on street-lamps, a liquid which will not congeal at the lowest temperature to which 35 the apparatus may be exposed and that will not readily evaporate is used—as, for instance, glycerin.

The operation of the apparatus constructed as described is as follows, it being assumed 40 that when there is no gas-pressure in cylinder d the liquid will be at a level I in both chambers of the apparatus, the valve r closing main-burner port s and the valve w closing igniter-burner port x : When the gas is turned on full by means of a cock in pipe B (not shown) at a time when the pressure in the main is least, as the daytime pressure, the liquid in cylinder d will be displaced, so 45 that its level will be at II, for instance, the liquid rising correspondingly in the chamber around said cylinder d , and further manipulation of the aforesaid cock in pipe B is unnecessary. This drop in the level of the liquid will have little effect on the floats M and 50 N , the ports s x remaining closed. When the pressure in the distribution is temporarily increased to a maximum, or what I may call a "lighting" pressure, one above the normal night pressure, the level of the liquid is displaced, say, to the point III, thereby causing 55 both floats to drop and unseat both valves r and w . In view of the fact that float M is secured to valve-stem o in a higher plane than float N , said float M will begin its appreciable downward movement before the float N . The downward distance moved by the float M when the level of the liquid is at III is such

as to cause the valve r to close the inner port t in passage of nipple a , and thus prevent the flow of gas from the inner chamber or cylinder d to the main burner F. On the contrary, 70 the extent of the downward movement of float N is comparatively small and so adjusted relatively to the like movement of float M that when the latter sinks to the level III to cause valve r to close port t the float N also reaches 75 said level to unseat valve w and allow gas to flow to the igniter-burner, such gas being ignited by the platinum sponge. The gas-pressure in the distribution is now reduced to normal night pressure, thereby causing the level 80 of the liquid to rise to a point intermediate of the points II and III—say to the point IV—causing float M to rise sufficiently to cause valve r to fully uncover port t , while the float 85 N rises to the limit of its upward motion, causing the valve w to close port x , and as the float M rises in advance of float N the gas issuing from the main burner will be ignited before the valve w cuts off the gas from the 90 igniter-burner. There is therefore no consumption of gas at the igniter-burner except for a moment, as will be readily understood.

On the outer end of the stem o and immediately above the double cone-valve r is arranged a downwardly-tapering regulating-valve q , which serves to control the volume of gas passing through port s under varying pressures. Should the pressure increase beyond the normal night or illuminating pressure, the level of the liquid in the apparatus will be correspondingly lowered, thereby drawing the regulating-valve q into port s to a greater or less extent, according to the extent of drop in such level, and correspondingly reducing the cross-sectional area of said port, and may drop to such an extent as to nearly close the port s and yet leave the port 100 practically wide open.

In Figs. 2 and 4 I have shown my invention in connection with an igniter-burner at which a constant flame is maintained until the main-burner flame is ignited, the modifications residing essentially in the arrangement and operation of the valves and the amplitude of their movements under variations of pressure. Thus the valve z controls the flow of gas to the main burner F through the port s only, said valve having a cylindrical body which constitutes a weight whereby the 110 float M and parts carried thereby are balanced in the liquid, while the float N and parts carried thereby are unbalanced or lighter. There is a further difference in that the cone-valve w' , that controls the flow of gas through 115 port x to the igniter-burner, instead of moving upwardly to close said port moves downward. In all other respects the apparatus is of the same construction as that shown in Figs. 1 and 3.

The operation of the apparatus shown in Figs. 2 and 4 is as follows: Supposing the level of the liquid in the apparatus when there is no gas-pressure on it to be at the point I,

the float M will be at such a level as to cause valve z to close port s while the float N will be at such a level above float M as to hold valve w' off its seat with port x wide open. 5 By turning on the gas at day pressure the level of the liquid in cylinder d will drop to point II, so that neither of the floats will be displaced, gas flowing to the igniter-burner nozzle l on pipe K, the gas being ignited once for all. When the pressure in the gas distribution is increased to night or illuminating pressure, the level of the liquid in d will sink to the point IV, thereby causing valve z to open wide port s and valve w' to close port x' ; but the float M will drop in advance of float N sufficiently to admit gas to the main burner and to admit of such gas being ignited by the igniter-burner flame before the float N has reached the limit of its downward motion with the falling level of the liquid to close the port x and cut off the supply of gas from igniter-burner nozzle l . On the other hand, when the gas-pressure is reduced to day pressure, causing the level of the liquid d to again rise to the point II, the float N will rise first, owing to the smaller load thereon relatively to the load on float M, and cause valve w' to uncover port x , so as to admit gas to said nozzle l , which gas is ignited by the main-burner flame before float M has moved upward sufficiently to cause valve r to cut off gas from the main burner.

Having thus described my invention, what I claim as new therein, and desire to secure by Letters Patent, is—

1. The combination with a gas-burner, a gas-supply pipe, a cut-off valve interposed between said burner and pipe and means operated by increase of the gas-pressure in the supply-pipe to move the valve off its seat; of means operated inversely to the direction of flow of gas from the supply-pipe to decrease the volume of gas supplied to the burner, substantially as and for the purpose set forth. 45 2. The combination with a gas-burner, of a gas-supply pipe, a gas inlet and cut-off valve interposed between said pipe and burner and means operated by variations of the pressure to move said valve to and off its seat; of a regulating-valve moved inversely to the direction of flow of gas from the supply-pipe to decrease the volume of gas supplied to the burner, substantially as and for the purpose set forth. 50

3. The combination with a gas-burner, a gas-supply pipe, a gas inlet and cut-off valve interposed between said burner and pipe and means operated by variations of the pressure in the supply-pipe to move said valve to and off its seat; of a regulating-valve moved by the cut-off valve inversely to the direction of the flow of gas from the supply-pipe for decreasing the volume of gas supplied to the burner, substantially as and for the purpose set forth. 55

4. The combination with a gas-burner, a gas-supply pipe, a cut-off valve interposed

between said burner and pipe, and a float connected to said valve and moved by the displacement of a liquid under the pressure of the gas from said supply-pipe; of a regulating-valve also moved by said float and operating to regulate the volume of gas supplied to the burner in accordance with the variations of the pressure of the gas on said liquid, for the purpose set forth. 70

5. The combination with a gas-burner, an igniter-burner, and a gas-supply pipe in communication with both burners; of a float-controlled cut-off valve for each of said burners, said floats moved by the displacement of the level of a liquid by variations of the pressure thereon of the gas from the supply-pipe, for the purpose set forth. 80

6. The combination with a gas-burner, an igniter-burner, and a gas-supply pipe in communication with both burners; of a float-controlled cut-off valve for each of said burners, said floats moved by the displacement of the level of a liquid by variations of the pressure thereon of the gas from the supply-pipe, and means for imparting a differential movement to said floats, for the purpose set forth. 85

7. In an automatic gas-lighting apparatus, the combination with a casing divided into concentric chambers, the inner chamber open at its lower end, the outer chamber in communication with the atmosphere at its upper end, a sealing liquid in said chambers the normal level of which is below said communication, a gas-supply pipe extending into the inner chamber above said normal level, a main burner and an igniter-burner both in communication with said inner chamber above the said normal level of the sealing liquid; of a float-controlled cut-off valve for each of said burners, and means for imparting to the floats a differential movement when the level of the sealing liquid drops below a normal level under an increase of the pressure in the inner chamber, for the purpose set forth. 90 100 105

8. In an automatic gas-lighting apparatus, the combination with a casing divided into concentric chambers, the inner chamber open at its lower end, the outer chamber in communication with the atmosphere at its upper end, a sealing liquid in said chambers the normal level of which is below said communication, a gas-supply pipe extending into the inner chamber above said normal level, a main burner and an igniter-burner both in communication with said inner chamber above the said normal level of the sealing liquid; of a float-controlled cut-off valve for each of said burners, and means for imparting to the floats a differential movement when the level of the sealing liquid drops below a normal level under an increase of the pressure in the inner chamber and when said level again rises to its normal level under a decrease of said pressure, for the purpose set forth. 110 115 120 125 130

9. In an automatic gas-lighting apparatus,

- the combination with a casing divided into two concentric chambers, the inner chamber open at its lower end, the outer chamber in communication with the atmosphere at its upper end, a sealing liquid in said chambers the normal level of which is below said communication, a gas-supply pipe extending into the inner chamber above said normal level, a main burner, and an igniter-burner provided with a platinum-sponge igniter; of a float-controlled valve for each of said burners, means for limiting the movements of the floats in either direction and means for imparting to them a differential movement when the level of the liquid sinks below or returns to its normal level under variations of gas-pressure, for the purpose set forth.
10. In an automatic gas-lighting apparatus, the combination with a casing divided into two concentric chambers, the inner chamber open at its lower end, the outer chamber in communication with the atmosphere at its upper end, a sealing liquid in said chambers the normal level of which is below said communication, a gas-supply pipe extending into the inner chamber above said normal level, a main burner, and an igniter-burner provided with a platinum-sponge igniter; of a float-controlled valve for each of said burners, the float for the igniter-burner cut-off valve being immersed to a greater extent in the seal-

ing liquid than the float for the main-burner valve, for the purpose set forth.

11. In an automatic gas-lighting apparatus, the combination with a casing divided into two concentric chambers, the inner chamber open at its lower end and the outer chamber in communication with the atmosphere at its upper end, a sealing liquid in said chambers the normal level of which is below said communication, a gas-supply pipe extending into the inner chamber above said normal level, a main burner and an igniter-burner both in communication with said inner chamber above the level of the liquid therein; of a double-cone float-controlled valve, controlling the inlet and outlet of the passage leading from the inner chamber to the main burner, a float-controlled cut-off valve for the igniter-burner, and means for imparting a differential movement to the floats when the level of the liquid falls below or returns to its normal level under variations of the pressure in the inner chamber, for the purpose set forth.

In testimony whereof I have signed my name to this specification in the presence of two subscribing witnesses.
